ATTORNEY.

UNITED STATES PATENT OFFICE

WILLIAM F. HELMOND, OF WEST HARTFORD, CONNECTICUT, ASSIGNOR TO UNDERWOOD ELLIOTT FISHER COMPANY, OF NEW YORK, N. Y., A CORPORATION OF DELAWARE

TYPEWRITING MACHINE

Application filed June 15, 1928. Serial No. 285,599.

This invention relates to devices for holding cards, envelopes and small work-pieces against the front of a rotatable platen of a typewriting machine.

5 In Patent 1,302,161 granted to me April 29, 1919, is illustrated a card-holder bearing on the front of the platen and stationary while the platen travels, in an Underwood typewriting machine. In said patent the 10 card-holder is of considerable width, as it extends some distance at each side of the printing point so as to afford as much support as practicable for long cards.

It is moreover customary in manufacturing all Underwood typewriting machines, to provide upon every machine a pair of brackets, numbered 44 in said patent, to form a foundation upon which to mount the card-holder. There has also been regularly provided the pin 50, upon which to anchor the card-holder spring. The provision of these parts on a large number of machines is burdensome, inasmuch as the card-holders of said patent are used only on a portion of 25 the manufactured product.

It is therefore a feature of this invention that permanent card-holders can be built into the machine at but a trifle greater cost than is involved in building in merely said 20 brackets and pins, so that all purchasers may get the benefit of the card-holder without cost, and the card-holder is so contrived that it is a constant benefit to the user in numerous ways.

35 It is an object of the present invention to equip every Underwood machine regularly with card-holding means instead of supplying the same as an expensive attachment, as in said patent. The card-holding means is 40 made inexpensive and simple, and one object is to make same of such attractive appearance that it will aid in the selling of the machine.

It is a feature of the present invention to 45 increase the duration of the control of the traveling card by the work-holder, and to control cards of greater length. This is done without increasing the bulk of the card-holder of said patent.

50 It is another feature of the present inven-

tion to give more clearance or expose more of the work to the operator in the vicinity of the printing point, to accommodate the making of corrections and also to give an uninterrupted view of all, or nearly all, of the 55 last word that has been written, so that the operator will not have to move the carriage back and forth to spell out the last word.

Another feature of the invention is to overcome the objection inherent in the use of any 60 stationary card-holder, which arises from the habit of the operator to swing into use the front central paper-guide finger which is usually provided on the Underwood carriage. This finger is of assistance in guiding a card, but if it is brought into use with the card-holder, as disclosed in said patent, it will collide therewith. It is a feature of the present invention to construct the card-holder so as to dispense with the use of such 65 swingable finger.

To these and other ends, the present invention provides a pair of card-holding units, placed one at each side of the printing point 70 sufficiently separated to disclose the entire 75 last word that has been written, and to guide long cards and envelopes, and having the other advantages above mentioned. These card-holders have independent springs, and hence each presses independently against the 80 platen, so that the card is held firmly at two widely separated locations. The spring may accordingly be made relatively weak, and either card-holder may be easily pulled forwardly away from the platen when not required, as only a single weak spring has to 85 be overcome instead of two strong springs, as in said patent.

The invention obviously affords a wider 90 range of manipulability and capacity than is afforded by the card-holder of said patent, and has other obvious advantages. The card-holders are very simple, and since they are duplicates they can be made so cheaply in 95 large quantities, as to render it practicable to build them into the typewriting machines without additional cost to the purchaser. These card-holders are mounted upon the same structure which controls the front sta- 100

tionary wing-scale that shifts up and down with the platen.

For the purpose of cheapening them and simplifying them to the required point, the device is reduced practically to two parts, namely, the struck-up bracket which is secured onto the shifting bar of the Underwood front scale, and the card-holder itself, which is also struck-up from sheet-metal.

10 There is also employed a spring, which releasably retains the card-holder upon the bracket and also holds the card-holder either back in working position or forward out of working position.

15 There is afforded good visibility at the printing line, and the device is of cheap, simple, rugged, compact and accessible construction, effective to hold small, stiff work-pieces securely in place upon the platen, while not 20 obstructing in any way the general operation of the machine.

The device presents easily mountable compact card-holding units, each unit including a simply stamped holder-frame or bracket 25 having forwardly-extending upper side portions, in which to mount loosely the work-holder or finger proper. Notches in the upper sides of said bracket provide bearings in which to carry lateral projections or gudgeons of said swingable finger. Lower opposed notches are also provided in the mount or bracket, to receive loosely a bolt, rung or cross-piece to form an anchorage for a loosely connected spring, which is tensioned between said finger and said rung, to hold these 30 two elements on their seats. The spring is confined within a downwardly-extending cut-away of the fingers, and no solid connections are needed between the elements of the card-holding unit.

40 After the card-holding finger with its depending spring is placed upon the bracket, the cross-piece or rung at the lower end of the spring may be used as a handle to pull the spring downwardly and snap it in place in notches provided in the lower edges of the bracket sides, thereby tensioning the spring.

The card-holding finger may, when manipulated for operative or inoperative position, 45 engage fore or aft upon said rung, to be locked in either position. Hence this method of locking does not require additional elements.

50 Other features and advantages will hereinafter appear.

In the accompanying drawing,

55 Figure 1 is a fragmentary view in front elevation with parts omitted, showing the work-gage and holders mounted in juxtaposition to the platen.

60 Figure 2 is a vertical transverse section with some parts omitted, showing the work-gage and holder in co-operative position with the platen.

65 Figure 3 is an enlarged sectional view sim-

ilar to Figure 2, but showing the holder swung away from the platen.

70 Figure 4 is a perspective view of one of the holders, assembled and mounted on its base, in working position.

75 Figure 5 is a perspective, showing the parts in Figure 4 disassembled.

Figure 6 shows a detached card-holding unit and indicates the novel manner of readily assembling the spring thereon.

80 Levers 13 actuate shift-frame 14 in a well-known manner, to raise or lower a frame 15, carrying a platen 16. Upon a type-bar segment 17, are mounted spring-brackets 18, carrying rollers 19 having peripheral flanges 20.

85 The shift-frame 14 has pivots 21 on which are fulcrumed a floating frame 22, normally held on said pivots by springs 23, as shown. The floating frame 22 has portions of its top bent up to form flanges 24.

90 Portions of said flanges from tongues 25 having slots 26, over which travel the flanges 20 on rollers 19. Other portions of flanges 24 engage screws 27 which hold spring-brackets 28, attached by rivets 29 to a work-gage 30, graduated along its upper edge to form a scale.

95 By means of oversized slots 31, in the spring-brackets 28, the work-gage 30 is adjustable vertically or horizontally. The flanges 24 also engage screws 32, by which is attached the novel holder-frame 33, bent to form forwardly-projecting sides 34.

100 In said sides 34 are bearings in the form of V-shaped cutouts 35, each open at the top to form prongs 36 on each side. In the bottom edges of sides 34 are inverted cutouts 37, forming bearings. Normally resting in the latter are bearing-ends 38 of a pin or

105 rung, which may have the form of a roller 39, said bearing-ends projecting from shoulders on the rung. Said shoulders prevent the rung from sliding through the cutouts 37.

110 The rung has near its center a circumferential groove 40, which retains the lower hooked end of a coil-spring 41. The upper end of spring 41 is hooked through a hole in the work-holding finger 42. The lower part of

115 the latter is formed into two legs 43, by means of an intermediate inverted cutout 44. This cutout gives clearness to the spring 41, permitting it to swing during a forward or backward canting of said finger. Also to give clearance to said coil-spring 41 there is provided a cutout 45 in the rear wall of the

120 holder-frame 33.

125 From each side edge of the finger 42, above the bottom edges thereof, and seated in the V-shaped bearings 35, project gudgeons 46. These act as pivots for the finger 42, and permit backward or forward pivotal movements

130 of the finger, towards or away from the platen. Stops 50 abut against the top edges of sides 34, to arrest the finger in its forward movement.

135 In order to find room for the device in the

compact machine, the bearing 38 for the rung 39 is located at a point in the bracket not far below the bearing for the gudgeon 46. Owing to the closeness of these two bearings, an extremely powerful spring would naturally be required, to hold the finger 42 against the work, Figure 2, inasmuch as said bearings are so close one to the other that the spring would be but slightly distended in swinging from either extreme to a midway position. Moreover, the finger would be apt to stand in its midway or dead-center position. Provision is, however, made whereby the spring is distended abnormally and considerably in passing through the midway position. To this end, the finger is extended downwardly at 43 beyond the gudgeon 46, and reaches to a point suitable for engaging the roll or rung 39, to force it down. Thereby the finger 42 stretches and tensions the spring 41 very much as the finger passes through its dead-center or vertical position. Thus the spring receives extra power for snapping the finger to either front or back position, and the liability of the finger remaining in the midway position is eliminated. Moreover a weaker spring can be employed than would be the case if the extensions 43 were to be eliminated. The distended spring also tends to snap up the rung 39, thereby forcing backward or forward rotation of the finger, so that the latter is acted upon in two ways, one way being in the direction of the longitudinal pull of the spring, and the other way being due to the camming effect produced by the rung upon the finger as the spring strains said rung upwardly. Thus the spring not only attaches the rung to the bracket, and attaches the finger also to the bracket, but it also holds the finger forcibly against the platen, and by reason of its extra tension at the dead-center point of the finger, it acts in a lively manner to throw the finger either forwardly or backwardly, so that it will not rest at dead center.

The upper portion of each finger 42 is preferably of triangular shape, with a triangular cutout 47. The top of said finger is not only rounded at the tip, but also has its apex bent forwardly as at 48. This forward curve lessens the sliding friction between said holder-plate and the surface of the work-sheet or member 49, and also facilitates the grasping of said holder-plate when desirable to pull the same away from the platen.

The coil-spring 41 is easily and readily removable and replaceable. To remove the same it is only necessary to lift the finger 42 out of the V-shaped bearings 35, and when the gudgeons 46 clear the prongs 36, the finger is swung forward and down slackening the spring and permitting the attached rung 39 to drop out of its open bearing 37.

A spring of less or greater tension may now be readily substituted.

It will be seen that gage and holding elements are preferably mounted on a one-piece member which is floatingly connected to the case-shift frame. This mounting maintains a fixed relation between said elements and the platen, whether the latter be in upper or lower case-shift position. The floating frame or member is guided in its vertical movements by the plurality of flanged rollers projecting into slots provided on said frame. These rollers are carried on spring-brackets ordinarily attached to the type-bar segment. This permits the rollers to yieldingly maintain the gage and holders against the platen at any of its vertical positions. At the same time a peripheral flange on the rollers by engaging the sides of the slots prevents any movement of the floating frame lengthwise of the platen.

The downward pull of the springs 41 holds the gudgeons in the bottom angle or fulcrum of the V-shaped cutouts. The pins 39 hold down and are held up by the springs, which are attached to the fingers above their gudgeons. Said fingers extend above the points of attachment of the springs. Said brackets are preferably formed of single strips of metal cut out and stamped up to the proper contour to afford light simple members easily manufactured.

The finger 42 can readily be swung back against the platen, or to a forward position clear of the platen. After passing the dead center, the spring pulls the finger to either operative or inoperative position. During a reciprocative movement of the holder-plate its legs over-ride the pin, to give a snap to the finger.

The two widely separated small fingers afford better visibility of the work than the patented single large work-holder.

The two independent holders make it practicable to hold on the platen a narrow card or label.

It has been seen that the work-holding unit includes a notched bracket into which a holder is inserted. The holder has pivotal bearings in the upper notches of said bracket which enable it to be swung forward away from the platen to an ineffective position or to be swung back towards the platen to an effective position. The holder is held in either position by a double acting spring which is fastened at one end to said holder and at its other end to a roller mounted in lower notches in the bracket. The roller is formed with a central groove in which the end of the spring is seated to retain it in center position. The spring, being so fastened, tends to pull the roller upward and simultaneously pull the holder downward, thereby retaining both the roller and holder in their respective notches in the bracket.

The work-holding finger 42, the spring 41, and the pin 39 as a whole may be easily

located upon the holder-frame 33, and the spring mounted in a novel manner as mentioned above and as clearly indicated in Figure 6.

5. Variations may be resorted to within the scope of the invention, and portions of the improvements may be used without others.

Having thus described my invention, I claim:

10. 1. The combination with a platen, of a support located in juxtaposition to said platen, a bracket on said support, upper and lower notches in said bracket, a holder resting in said upper notches, a rung mounted in said lower notches, and a spring for retaining said holder and rung in said notches.

2. The combination with a platen, of a support located in juxtaposition to said platen, a bracket on said support, upper and lower notches in said bracket, a holder detachably resting in said upper notches, a roller mounted in said lower notches, and a spring for retaining said holder and roller in said notches to be depressible by the holder 20 against the tension of the spring, said notches being open to permit insertion or removal of said roller and said holder.

3. The combination with a platen, of a support located in juxtaposition to said platen, a bracket on said support, a work-holding member extending down into said bracket, arms on said member extending through openings in said bracket to form pivots upon which said member may be swung to an 30 operative or an inoperative position, a yieldable rung mounted in said bracket, and a spring effective to hold said rung in place, to prevent accidental displacement of said member, said swinging work-holding member having means to force said rung to yield 40 against the pressure of said spring, as the work-holding member is swung forward and backward.

4. The combination with a platen, of a support located in juxtaposition to said platen, a bracket on said support, a work-holding member extending down into said bracket, arms on said member extending detachably through openings in said bracket, 50 said openings forming pivotal bearings upon which said member may be swung to an operative or an inoperative position, a rung detachably mounted in said bracket, and a spring effective to hold said rung and said member attached to the bracket, said spring also being effective to hold said member in either its operative or inoperative position.

5. The combination with a platen, of a support located in juxtaposition to said platen, 60 a bracket on said support, a detachable work-holding member extending down into said bracket and movable bodily up and down thereon, arms on said member extending detachably through openings in said bracket 65 to form pivots upon which said member may

be swung to an operative or an inoperative position, a roller yieldably mounted in said bracket to engage said member, and a spring connected to said roller and to said member for retaining both roller and member in said bracket, said spring co-operative with said roller to enable the roller to resist the swinging back or forth of the work-holding member to prevent accidental displacement of said work-holding member.

6. The combination with a platen, of a bracket located in juxtaposition to said platen, a spring-pressed work-holding member having legs extending down inside said bracket, projections on said legs extending through said bracket to form a fulcrum whereon said member may swing from an operative to an inoperative position, the platen limiting the movement of said member when swung to its operative position, and means on said legs engaging said bracket to limit the movement of said member when swung to its inoperative position.

7. The combination with a platen, of a work-holder, a mount in which said work-holder is pivoted, said work-holder extending from its pivot towards the platen, a spring thrusting said work-holder down, an obstacle provided in said mount and in the path of said work-holder, to be forced down by the work-holder in its forward and backward swinging movements, and a stop to arrest the work-holder in its forward position, said spring effective to retain the work-holder either in its forward position against said stop, or in its rear effective position; the spring being connected to said obstacle and tensioned thereby and tending to restrain the work-holder from surmounting and passing said obstacle.

8. The combination with a platen, of a swinging work-holder having trunnions projecting therefrom, a mount having opposite sides provided with bearings in which said trunnions work, said work-holder extending towards the platen and being movable up and down in said mount, a downwardly-tensioned spring connected to said work-holder above the trunnions, and a yieldable rung in said mount, said work-holder having a projection below its trunnions, and said rung being in the path of said projection to form a yieldable obstacle when the work-holder is pressed forwardly or backwardly on its trunnions, said spring tending to restrain said work-holder from mounting and passing said rung in either direction, and also effective to hold said work-holder back against the work.

9. The combination with a platen, of a work-holder having trunnions projecting therefrom, a mount having opposite sides provided with bearings in which said trunnions work, said work-holder extending towards the platen, a downwardly-tensioned spring connected to said work-holder above

the trunnions, and a rung in said mount, said work-holder having a projection below its trunnions, and said rung being in the path of said projection to form an obstacle when 5 the work-holder is pressed forwardly or backwardly on its trunnions, said spring tending to restrain said work-holder from mounting and passing said rung in either direction, and also effective to hold said work-holder back 10 against the work, said mount having in said sides open slots in which said rung is detachably retained by said spring.

10. The combination with a platen, of a work-holder having trunnions projecting 15 therefrom, a mount having opposite sides provided with open bearings in which said trunnions are detachably seated, said work-holder extending towards the platen, a spring connected to said work-holder, and a rung in 20 said mount, said work-holder having a projection below its trunnions, and said rung being in the path of said projection to form an obstacle when the work-holder is pressed forwardly or backwardly on its trunnions, 25 said spring tending to restrain said work-holder from mounting and passing said rung in either direction and also effective to hold said work-holder back against the work, said spring having the form of a double-acting 30 draw spring connected at its upper end to said work-holder, and the latter being removably retained upon said mount by said spring.

11. The combination with a platen, of a detachable work-holder having trunnions, a 35 mount provided with bearings in which said trunnions work, said work-holder extending towards the platen, a spring connected to said work-holder above the trunnions, and a detachable rung in said mount, said work-holder 40 having a projection below its trunnions, and said rung being in the path of said projection to form an obstacle when the work-holder is pressed forwardly or backwardly on its trunnions, said spring tending to restrain 45 said work-holder from mounting and passing said rung in either direction, and also effective to hold said work-holder back against the work, said spring having the form of a double-acting draw-spring connected at its upper 50 end to said work-holder, said trunnions projecting from said work-holder, said bearings open at the top to permit withdrawal of said work-holder from said mount, and said spring effective to hold both said work-holder and 55 said rung attached to said mount.

12. The combination with a platen, of a work-holder, a mount upon which said work-holder is pivotally supported, and from which it extends upwardly to press back the 60 work, a spring connected to said work-holder, and means provided upon said mount to form a yieldable obstacle in the path of said work-holder, said spring anchored at its lower end upon said obstacle and tending to cause the 65 obstacle to restrain said work-holder from

mounting and passing said obstacle, and also effective to hold said work-holder back against the work.

13. The combination with a platen, of a swinging work-holder, a mount upon which 70 said work-holder is pivotally supported and upon which it can move up and down, and from which it extends upwardly to press back the work, a bodily-detachable spring connected to said work-holder, and means provided upon said mount to form a yieldable obstacle in the path of said work-holder, said spring anchored at its lower end and tending to cause the obstacle to restrain said work-holder from riding over said obstacle, and also effective to hold said work-holder back 75 against the work, said obstacle in the form of a depressible rung which is detachably held upon said mount by means of said spring.

14. The combination of a swinging work-holder, a mount upon which said work-holder is pivotally supported and upon which it can move up and down, a spring connected to said work-holder, and means provided upon said mount to form a yieldable obstacle in the path 80 of said work-holder, said spring anchored to said obstacle and tending to cause the obstacle to restrain said work-holder from riding over said yieldable obstacle, and also effective to hold said work-holder against the work, said 85 work-holder and said obstacle being held attached to said mount by means of said spring.

15. The combination with a platen, of a work-holder, a mount having open bearing 90 upon which said work-holder is pivotally and removably supported, and from which it extends upwardly to press back the work, a bodily-detachable spring connected to said work-holder, and a rung provided upon said mount to form an obstacle in the path of said 95 work-holder, said spring anchored at its lower end to said rung and tending to restrain said work-holder from mounting and passing rung, and also effective to hold said work-holder back against the work, said work-holder, said rung and said spring being removable from said mount, and said spring holding both the work-holder and the rung attached to said mount.

16. A four-part attachment for holding 115 work upon the front of a typewriter-platen, including a mount having sides formed with open upper bearings, a work-holding finger having trunnions detachably inserted in said bearings, whereby it may swing rearwardly 120 against the platen or forwardly away therefrom, said mount being also provided with open lower bearings, a rung caught in said lower bearings, and a spring caught upon said rung to hold it up in said lower bearings and also caught upon said finger to hold it down in said upper bearings in both forward and rearward positions of the finger, said spring holding said finger, said rung and itself all 125 attached to said mount.

17. The combination of a mount, having sides provided with bearings, a work-holding finger having trunnions in said bearings, a draw-spring attached to said finger above the 5 trunnions to hold it down in the bearings, a movable anchorage for the lower end of the finger, said spring connected to said anchorage to hold it in normal position, and

means to enable said finger when swung upon its trunnions to depress said anchorage and thereby tension the spring, said anchorage reacting forwardly or backwardly against said finger to aid in swinging the finger upon 70 its trunnions.
